UNITED STATES PATENT OFFICE.

GEORGE W. ANDERSON, OF HAMILTON, OHIO, ASSIGNOR OF ONE-HALF TO DANIEL P. HAYES, OF HAMILTON, OHIO.

SWITCH.

1,112,965.

Specification of Letters Patent.

Patented Oct. 6, 1914.

Application filed November 29, 1913. Serial No. 803,748.

To all whom it may concern:

Be it known that I, GEORGE W. ANDERSON, a citizen of the United States, residing at Hamilton, in the county of Butler and State of Ohio, have invented new and useful Improvements in Switches, of which the following is a specification.

The present invention relates to improvements in switches for railway rails.

- 10 In carrying out my invention, I propose to provide an arrangement of rails wherein no gap will be left at the points where the rolling stock travels either from the main line to a side line, or from the side line to the 15 main line, and which will obviate the shock and jar usually occasioned by the wheels of the rolling stock, passing over the gap in the rails or uneven surfaces at the switch of the rails. I also propose to provide a 20 rail structure wherein the switch points will be received in suitable recesses in the rails with which they abut so that no shoulder or projecting surface will be offered to the wheels of the rolling stock.
- 25 It is still a further object of the invention to provide the rails upon their inner faces with slots or openings to receive the ends of switch points, the said openings having rail filler plates which are slidable therein 30 and which are adapted to be alternately and automatically brought to the surface of either of the rails to fill the gap caused by the opening in either of the rails after one of a pair of switch points has been moved 35 to have its end received within the gap or opening of the second or opposite rail.

With the above objects in view, and others which will appear as the nature of the invention is more fully understood, the improvement resides in the construction, combination and operation of parts set forth in the following description and falling within the scope of the appended claims.

40 In the drawings Figure 1 is a perspective view illustrating rails constructed in accordance with the present invention, and showing the switch open to the main line. Fig. 45 2 is a plan view showing the switch open to the side line. Fig. 3 is a transverse sectional view on the line 3—3 of Fig. 2. Fig. 50 4 is a longitudinal sectional view on the line 4—4 of Fig. 2. Fig. 5 is a plan view, with switch points removed. Fig. 6 is a bottom plan view. Fig. 7 is a vertical longitudinal 55 sectional view upon the line 7—7 of Fig. 2.

Fig. 8 is a perspective view looking from the inner face of one of the rails, the filler plate being removed. Fig. 9 is a detail perspective view of one of the filler plates, the rocker members and the links connecting the 60 rocker members with the plate. Fig. 10 is a perspective view of the sliding frame, and Fig. 11 is a perspective view of one of the switch points.

The rails for the main line are indicated 65 by the numerals 1, and those for the side line are indicated by the numerals 2. As it is one of the primary objects of my invention to provide means for directing a train from the main line to the side line, or vice 70 versa, without the employment of frogs or the like, one rail of the side line 2 comprises a continuation of one of the rails of the main line, and the rail at the juncture of the main and side lines, has its inner face provided 75 with a longitudinally arranged slot 3 the inner wall of which being vertically straight and arranged in a plane with the web of the said rail. The slot or recess 3, it will thus be noted, is provided by cutting the head 80 and base flange of the rail. The web of the rail, at the opposite ends of the slot 3 is formed with enlargements 4 which have their outer faces formed with inwardly extending lips 5, so the said slots provide, 85 what may be termed a flanged way. The opposite rail 1 is constructed or formed in a similar manner, the slot 3 thereof being arranged diametrically opposite the slot or guideway above described.

90 Arranged within each of the depressions 3 is a filler plate 6. Each of these plates is of a thickness corresponding to the depth of the guideway, and each of the said plates has its opposite end contacted by the lips 5 of the web enlargements 4, and the upper and inner corners of each of the said plates is rounded to agree with the rounded corners of the rails. The filler plates 6, adjacent their opposite ends, are provided with 95 ears 7, arranged in spaced pairs, and between each of the said pairs of ears is pivotally connected a link 8. These links in turn are pivotally secured to the bifurcated ends of arch-shaped rocker members 9, and 100 the said rocker members are in turn pivotally secured to the inner faces of ties or beams, 10 and 11 respectively, which support the rails at the portions thereof provided with the slots 3. The ends of the 105 110

beams or ties 10 and 11 are slotted upon their inner faces adjacent their ends to provide for the reception therebetween of the filler plates and also to properly arrange the inner faces of the said ties or beams to receive the pivots of the rocker members 9. Two of the rocker members are pivoted for each of the filler plates 6, and the concaved edges of all of the rocker members are disposed toward the upper faces of the ties, and, as will be understood, each pair of the rocker members are disposed diametrically opposite each other.

Connected with the ties 10 and 11 below the portions thereof upon which the rails rest, are bearing plates 12 and 13 respectively, and these plates have their upper faces each formed with a pair of spaced depressions 14, the depressions upon one of the plates being disposed diametrically opposite the depressions of the second plate. These depressions are adapted to serve as guideways for transversely arranged bars, 15 and 16, provided upon a sliding frame 17. The ends of the bars 15 and 16 have connected thereto, upon their upper faces, filler plates supporting blocks 18 and 19 respectively. The blocks 18 and 19 are of a thickness equaling the distance between the upper edges of the plates 6 and the upper faces of the heads of the rails. The blocks 18 and 19 have their inner faces inclined downwardly toward the base bars 15 and 16, as indicated by the numerals 20, while the bar 15 is provided with vertically disposed studs 21 and 22 respectively, each of the said studs being spaced a slight, but suitable distance from the respective blocks 18 and 19. The plates 6 are arranged to have their lower edges contacted by the beveled edges 20 of the blocks 18 and 19, when the frame 17 is moved longitudinally so that one of the said filler plates 6 will be guided by the said inclined wall 20 to the top and bearing face proper of the block, and so support the plate in a proper position when the same fills the gap or opening in the rail and is disposed flush with the top of the head of the rail. In this connection it should be stated that the blocks 18 and 19 are so spaced upon the frame 17 as to permit one of the said blocks supporting one of the filler plates 6 to hold the same flush with the rail, as just set forth, while the second block will have moved with the frame a distance sufficient to permit the second plate gravitating below the plane of the upper surface of the second rail.

The numerals 24 and 25 designate the movable switch points, which, in the present instance are connected through the medium of rectangular plates 26 and 26¹, secured to the inner base flanges of the points. The points are, of course, arranged between the rails, and have their outer faces, adjacent the depressions 3 in the main rails 1 beveled

or inclined in the usual manner, so that the inclined sides of the rail switch points will contact with the opposite rails, but, in the present instance, I have provided the said inclined faces with head enlargements 28 70 which are arranged upon the sides to be received within either of the depressions or slots 3 of the rails, in accordance with the direction in which the points are moved. The ends of the switch points, upon the 75 lower faces or base portions are provided with longitudinally extending, integrally formed bosses which provide, what I term, rocker actuating members 29. The outer ends of the actuating members terminate a 80 suitable distance from the base portions of the switch points, so that the ends of the base proper of the said switch points will rest upon the tie or beam 11, and the actuating members 29 are of a length approximately equal or slightly less than the distance between the ties or beams 10 and 11, so that the said members project downwardly between the said beams and are each received upon one pair of the rocker members 90 9 and disposed each adjacent one of the studs 21 and 22 respectively.

Suitable means is provided for throwing switch points, a rod R, connected with an operating lever L being illustrated in the 95 drawings to accomplish this purpose, but, of course, any other suitable actuating members may be employed.

The operation of the device may be briefly described as follows: We will suppose that 100 the side line is open, as shown in Fig. 2, and it is desired to close the side line and open the main line as shown in Fig. 1 of the drawings. The lever L is thrown outwardly which causes the actuating member 29 of the 105 switch point 25 to contact with the stud 21 and moves the frame 17 in the direction of the lever L. The actuating member 29 also engages with the rockers 9 to tilt the said rockers to cause the same, through the medium of the links 8, to move the plate 6 vertically to fill the slot 3 and to position the block 18, which has been moved by the frame 17, to underlie and support the said plate 6. Simultaneously with this action the actuating member 29 of the switch point 24 has moved upon the rocker members 9 connected with the links 8 of the filler plate 6 of the rail nearest the lever L, to move the said filler plate downward of the slot 3, the supporting block 19 having been moved with the frame 17 from below the said filler plate, to permit of the switch point 24 being received within the said slot 3. By swinging the lever L in an opposite direction or toward the track, the switch points may be again thrown to the position illustrated in Fig. 2, as will readily be understood.

From the above description, taken in connection with the drawings the simplicity 130

and the advantages of the device will, it is thought, be perfectly understood by those skilled in the art to which such inventions appertain without further detailed description.

5 Having thus described my invention what I claim is:—

1. In combination, two rails, each of said rails having their inner faces slotted, filler members within the slots, switch points between the rails, means for operating the switch points to permit one of the said points being received within the slot of one of the rails, and mechanism operated by the moving switch points for elevating one of the filler members to fill the space provided by the slot in the second rail.

2. In combination, main rails and side rails and switch points between the main and side rails, the main rails having their inner faces depressed, filler plates within the depressions, and means actuated by a movement of the switch points for alternately raising and lowering one of the filler blocks 25 to fill the gap provided by the depression when the second gap is occupied by the end of one of the switch points.

3. In combination, main rails and side rails, and switch points between the main and side rails, the main rails having their inner faces depressed, filler plates vertically movable within the depressions, means actuated by a movement of the switch points for alternately raising one of the switch points 35 to fill the gap provided by one of the depressions and to lower the second filler plate when the depression provided therefor is occupied by one of the switch points.

4. In combination, main rails and side rails, and connected switch points between the main and side rails, means for moving the switch points toward either of the main rails, the said main rails having their inner faces depressed, filler plates within the depressions, mechanism actuated by the movable switch points for alternately raising one of the switch points to fill the gap provided by the depression and to lower the second filler plate to permit of one of the switch 50 points having its end received within the depression of the second rail, and means connected with the mechanism for supporting the elevated filler plate.

5. In combination, main rails and side rails, and switch points between the main and side rails, filler plates within depressions and having their upper portions correspond with the heads of the rails, means for swinging the switch points to permit the end of one of the said points entering the depression in one of the rails, mechanism actuated by the switch points for operating the filler plates to alternately raise one of the said plates and lower the second plate, 60 the lowered plate being disposed below the

point arranged within the depression of one of the rails, the second plate being flush with the head and side of the head of the second rail.

6. In combination, main rails and side rails, and connected switch points between the said main and side rails, the main rails having their inner faces depressed to receive the ends of the switch points, a filler member within each of the depressions, and means for lowering the filler plate below the switch point within the depression of one of the rails and elevating the plate in the second rail to fill the depression thereof.

7. In combination, main rails and side rails, and connected switch points between the main and side rails, the main rails having their inner faces provided with diametrically opposite depressions, means for operating the switch points to bring the end of one of the said points to within the depression of either of the rails, filler plates one within each of the depressions, and adapted to automatically fill the gap in the depression of the rail opposite to that filled by one of the switch points.

8. In combination, main rails and side rails, and connected switch points between the main and side rails, said switch points having one of their ends pivoted and their second end provided, upon their beveled sides with head projections, the main rails having diametrically opposite depressed portions, one of which adapted to receive the head projection of either of the switch points, the filler plates vertically within each of the depressions, and mechanism actuated by the switch points for alternately raising and lowering the opposite filler plates to cause one of the same to be elevated flush with the top and side of the head of the rail when the second plate is lowered within its depression below the head projection of the switch point occupying the said depression.

9. In combination, main rails and side rails, and connected switch points between the main and side rails, the inner faces of the main rails having their heads and base flanges provided with longitudinal depressions, their webs enlarged and terminating in a plane with the end walls provided by the depressions, the said web enlargements having their outer faces formed with lips which extend within the gap provided by the depressions, vertically movable plates within the depressions and engaged by the lips of the web enlargements, means for throwing the switch points to bring the end of one of the said points to within the depression of one of the rails above one of the plates, and mechanism operated by the switch points for raising the plate within the depression in the second rail to fill the gap provided by the said depression.

10. In combination, main rails and side

4. rails, connected switch points within the main and side rails, said switch points having their ends provided with head extensions, the main rails being depressed and 5 adapted to receive the head enlargement of one of the points, when the said point is moved toward the said rail, guide members arranged in a plane with the opposite vertical walls of the depressions and projecting 10 beyond the depressions to provide ledges upon which the head extensions of the points rest, filler blocks within the depressions, and means for lowering the filler block within 15 the depression occupied by one of the head extensions, and for elevating the block within the depression of the second rail to fill the gap provided by the said depression.

11. In combination, main rails and side rails, connected switch points between the 20 main and side rails, the main rails having their inner faces depressed, filler plates within the depressions a frame slidably arranged below the depressions, supporting blocks upon the frame, means for throwing the 25 switch points to bring one of the same to within one of the depressions, and mechanism operated by the switch points and connected with the filler plates and frame for simultaneously sliding the frame and actuating the filler plates to raise and lower the 30 said plates and to bring the supporting block out of engagement with the plate in the recess receiving the switch point and into supporting engagement with the second filler 35 plate to sustain the same elevated to a plane flush with the head of the rail.

12. In combination, main rails and side rails, connected switch points between the main and side rails, the main rails having 40 oppositely disposed depressions, vertically movable filler plates within the depressions, ties for the rails, arched rocker members pivoted to the ties, link connections between the plates and rocker members, rocker actuating members upon the switch points, and means for throwing the switch points to cause their actuating members to swing the 45 rocker members to lower one of the filler plates to permit of the reception of the end of one of the switch points within the depression of one of the rails and to elevate the second filler plate to fill the gap provided by the depression in the second rail.

13. In combination, main rails and side 50 rails, connected switch points between the main and side rails, throw mechanism for the switch points, the inner faces of the main

rails having depressions to receive the end of either of the switch points, a filler plate within each of the depressions, pivoted rockers, a link connection between the rockers and the plates, a movable supporting block for each of the plates, a depending member upon each of the switch points and engaging with the rocker member of each of the filler 60 plates and adapted to swing both of the rocker members to elevate one of the filler plates to fill the depression of one of the rails and to move the supporting blocks to cause one of the said blocks to underlie the 65 elevated filler plate and the second block to be moved from below the second filler plate to permit of the lowering of the said second plate and to position the end of one of the switch points within the depression above 70 the lower filler plate.

14. In combination, main rails and side rails, connected switch points between the main and side rails, means for throwing the 80 switch points, supporting ties for the rails and switch points, the main rails having their inner faces provided with oppositely depressed portions, vertically movable filler plates within the depressions, arched members pivoted to certain of the ties, link connections between the arched members and the filler plates, bearing plates secured to the under faces of the ties provided with the arched members, a slidable frame arranged upon the bearing plates, blocks having inner 85 beveled faces connected with the frame, a stud arranged adjacent each of the blocks, the inner lower edges of the filler plates being beveled, projecting members upon the switch points adapted to engage with the arched 90 members and within contacting relation to the studs, all substantially as and for the purpose set forth.

15. In combination, main rails and side rails, connected switch points between the 100 main and side rails, the switch points having their ends provided with head projections, the main rails having web reinforcements which terminate in horizontal ledges, means for swinging the switch points and to 105 bring the head extensions of the same over and into engagement with the ledges.

In testimony whereof I affix my signature in presence of two witnesses.

GEORGE W. ANDERSON.
